STACY B. HASELTINE, OF CHICAGO, ILLINOIS, ASSIGNOR TO WILLIAM H. MINER, OF CHAZY, NEW YORK.

DRAFT-RIGGING YOKE.

1,242,802.

Specification of Letters Patent.

Patented Oct. 9, 1917.

Application filed April 14, 1916, Serial No. 91,237. Renewed August 27, 1917. Serial No. 188,495.

To all whom it may concern:

Be it known that I, STACY B. HASELTINE, a citizen of United States, residing at Chicago, in the county of Cook and State of Illinois, have invented a certain new and useful Improvement in Draft-Rigging Yokes, of which the following is a full, clear, concise and exact description, reference being had to the accompanying drawings, forming a part of this specification.

This invention relates to improvements in draft rigging yokes.

The object of the invention is to provide a draft rigging yoke which may be detachably connected with all standard types of draw-bars whether the latter are provided with coupler key slots or not.

Another object of the invention is to provide a detachable draw-bar and yoke connection so arranged that all the parts are readily accessible at the front end of the yoke and wherein the draw-bar may be removed without disturbing the gear.

In the drawing forming a part of this specification, Figure 1 is a part longitudinal section and a part side elevation of a draw-bar and yoke showing my improvements in connection therewith, a friction gear being indicated diagrammatically by dotted lines, Fig. 2 is a broken horizontal sectional view taken substantially on the line 2-2 of Fig. 1. Fig. 3 is a vertical sectional view taken substantially on the line 3-3 of Fig. 1. Fig. 4 is a front end elevation of the yoke. Fig. 5 is a bottom plan of the yoke. And Fig. 6 is a perspective view of the locking block employed.

In said drawing, 10 denotes a standard draw-bar having an upper shoulder 11, lower shoulder 12, and 13 indicates a friction gear of a well known type. The yoke A, as shown, comprises an upper arm 14, lower arm 15, rear connecting piece 16, and a hollow rectangular hood or head at its front end, said hood having an upper wall 17, side walls 18-18, and bottom wall 19. The upper wall 17 is provided with a depending, transversely extending shoulder or gib 20 which cooperates with the draw-bar shoulder 11, said gib 20 being curved on its rear face as indicated at 21 to thereby permit radial movement of the draw-bar. The lower wall 19 of the hood, which is downwardly offset from the arm 15, is provided on its upper face with two longitudinally

extending channel shaped grooves or recesses 22-22 on opposite sides thereof, said grooves 22-22 thereby forming a central shoulder 23 between the grooves which terminates at the line indicated at 24, (see 60 Figs. 1 and 2). To detachably engage the draw-bar with the yoke, I provide a locking block B, said block B being substantially a flat member having an upwardly extending shoulder 25 at its front end which extends 65 transversely of the block B and is arranged to engage the lower shoulder 12 of the draw-bar. Said shoulder 25 is also convexly curved on its inner face as indicated at 26 to permit said radial movement of the draw-bar. At its rear end, the block B is provided with a pair of spaced, depending lugs or projections 27-27 which fit and slide within said recesses 22-22, said lugs 27 being spaced apart sufficiently to slide past 70 said shoulder or rib 23. The block B is also preferably tapered rearwardly so as to snugly fit against the side walls 18-18 which are also tapered for the purpose of permitting the radial movement of the 80 draw-bar. To retain the block B in position, I provide a rectangular plate 28 which is insertable and removable through vertically extending recess 29 in the bottom wall of the hood, said recess being so located that 85 the block 28 when in position will bear against the end 24 of said rib 23. The retaining plate 28 may be held in position by any suitable means such as the bolt 30 which passes through perforations in the 90 plate 28 and in depending ears 31-31 formed on the lower face of the hood. A slot 32 is provided at the rear of the hood in the bottom wall thereof to permit the insertion of a suitable tool to facilitate removal of the locking block.

The parts are shown in assembled relation in Fig. 1 and in order to disconnect the draw-bar, the bolt 30 is first removed, then the plate 28 is withdrawn downwardly, after 100 which the block B is pulled forwardly as far as possible with the lugs 27 in the grooves 22. When the block has thus reached its most forward position, it is then swung downwardly and to facilitate this movement, said block B is rounded at its rear edge as indicated at 33. As soon as the block B is removed, the draw-bar may be dropped down so as to clear the shoulder 20 whereupon the draw-bar may be withdrawn 110

forwardly through the open end of the hood. It is believed that the method of assembling the parts will be apparent from the foregoing description.

5. I claim:

1. A yoke having a hooded forward end provided with means for engaging the upper shoulder of a draw-bar, and removable devices for coöperating with the lower shoulder of the draw-bar, said devices including a shouldered locking block removable from the front end of the hood, and a retaining plate insertible through a slot in the bottom of the hood, said block having shoulders on its underside at the rear of said plate to engage the latter when the parts are operatively assembled.

2. A yoke having a hollow, rectangular head, the bottom wall thereof having a longitudinally extending slot on the inner face thereof, a locking block having an upwardly extending shoulder adapted to engage the lower shoulder of a draw-bar, said block having also a depending lug slidable within said slot, and a retaining plate insertible through a slot in said bottom wall adapted to engage said block and hold it in position.

3. A yoke having a hood at its forward end within which a draw-bar butt is adapted to be received, the bottom wall of said hood having a pair of longitudinally extending slots on the inner face thereof, a locking block removable through the open front end of said hood, said block having depending lugs movable within said slots, and a re-

taining plate for holding said block in operative position.

4. A cast yoke for railway draft riggings having a hollow hood at its forward end 40 within which is adapted to be received the butt of a draw-bar, the upper wall of said hood having an integral transversely extending shoulder and the bottom wall of said hood having a longitudinally extending 45 groove in the inner face thereof, a shouldered locking block insertible from the front of said hood, said block having a depending lug slidable within said slot, and a transversely arranged retaining plate insertible 50 through an opening in the bottom wall of said hood, said plate being located forwardly of said lug when the parts are assembled and thereby preventing said block from pulling out.

5. A yoke for draft riggings having a rectangular hollow head at its front end, said head being provided with integral means for engaging the upper portion of a draw-bar butt, and detachable devices for 60 engaging the lower portion of a draw-bar butt, said devices including a block having a shoulder on its upper face and depending lugs on its lower face, and a retaining plate insertible through an opening in the bottom 65 wall of the hood, said lugs engaging the rear face of said plate when the parts are in assembled position.

In witness that I claim the foregoing I have hereunto subscribed my name this 15th day of Mar., 1916.

STACY B. HASELTINE.
